[57] CLAIM

The ornamental design for a folding chaise lounge with wheels, as shown and described.

DESCRIPTION

FIG. 1 is a perspective view of the design, said view showing the design in a first position with the back of the chaise lounge raised to a vertically extending position; FIG. 2 is a top view of the design in said first position; FIG. 3 is a left side view of the design in said first position; FIG. 4 is a front view of the design in said first position; FIG. 5 is a rear view of the design in said first position; FIG. 6 is a perspective view of the design in a second position wherein the back of the chaise lounge is lowered to a substantially horizontal position;

FIG. 7 is a top view of the design in said second position; FIG. 8 is a left side view of the design in said second position;

FIG. 9 is a front view of the design in said second position; and,

FIG. 10 is a rear view of the design in said second position. FIGS. 2 through 5 have been shown on a larger scale with respect to FIG. 1 and FIGS. 7 through 10 have been shown on a larger scale with respect to FIG. 6 but FIG. 6 has also been shown on a larger scale with respect to FIG. 1.
